US00D384739S

United States Patent [19]

Dolan

[11] Patent Number: Des. 384,739

[45] Date of Patent: **Oct. 7, 1997

[54] COMBINED CEILING FAN HOUSING AND LIGHTING ASSEMBLY MOUNT

[76] Inventor: **Patrick Dolan**, 1020 SW Westwood Ct., Portland, Oreg. 97201

[**] Term: 14 Years

[21] Appl. No.: 53,230

[22] Filed: Apr. 17, 1996

Related U.S. Application Data

[63] Continuation of Ser. No. 29,549, Oct. 11, 1994, abandoned.

[51] LOC (6) Cl. 23-04

[52] U.S. Cl. D23/411; D23/377; D23/385

[58] Field of Search D23/377, 379, D23/385, 411; 416/5; D26/72, 59, 57, 81-86, 88; 392/364; 362/96

(List continued on next page.)

*Primary Examiner—Lisa Lichtenstein
Attorney, Agent, or Firm—Harold E. Meier*[57] **CLAIM**

The ornamental design for a combined ceiling fan housing and lighting assembly mount, as shown and described.

DESCRIPTION

FIG. 1 is a perspective view of a combined ceiling fan housing and lighting assembly mount, showing my new design;

FIG. 2 is an enlarged side view thereof, the other sides being identical to that shown;

FIG. 3 is an enlarged top view thereof; and,

FIG. 4 is an enlarged bottom view thereof.

The broken line showing of environmental structure in FIGS. 1 and 2 is for illustrative purposes only and forms no part of the claimed design.
